UNITED STATES PATENT OFFICE.

JULIUS TUTEUR, OF CLEVELAND, OHIO.

BEAM-END PROTECTOR AND ANCHORAGE.

1,137,099.

Specification of Letters Patent. Patented Apr. 27, 1915.

Application filed February 20, 1909. Serial No. 479,085.

To all whom it may concern:

Be it known that I, JULIUS TUTEUR, a citizen of the United States of America, and a resident of Cleveland, in the county of 5 Cuyahoga and State of Ohio, have invented certain new and useful Improvements in Beam-End Protectors and Anchorages, of which the following is a specification.

My invention relates to improvements in 10 beam end protector and anchorage, and has for its object the provision of a wall box for receiving wooden beams, which shall be simple, cheap and easily constructed. In a member of this character, it is desirable that 15 the wall, particularly if of brick, shall have the weight distributed over a considerable area, while the surrounding portions should be sufficiently spaced from the end of the beam, to prevent dry rot. Moreover, as the 20 device is not subjected to severe structural strains, any legitimate cheapening of the cost of manufacture, is highly desirable.

Accordingly, I have so constructed a protector of this class, that it may be formed 25 from a single sheet metal blank, if desired, and moreover, the expense of riveting the parts in place, including the anchorage member, may be entirely dispensed with in certain embodiments of my invention. Several 30 types thereof are herein explained and illustrated in the drawings, wherein:—

Figure I is a perspective view of one of said devices, formed from an integral sheet metal blank, wherein is positioned the supported beam end. Fig. II illustrates the blank from which said protector is formed. Fig. III is a plan view of the device, having dowel-pins inserted in the floor for anchorage members, and somewhat widely extended ends for further distributing the strain throughout a wall of soft brick construction. Fig. IV is a perspective view of a further modified construction, wherein the side pieces are riveted to the base, and a 45 separate anchorage member is employed. Fig. V is a plan view of the same, employing instead an integral anchorage member b'; and Fig. VI. is a front view of the device of Fig. III.

Throughout the several figures of the drawing, I have employed the same characters of reference to indicate similar parts.

Referring to the blank a, Fig. II, it will be seen that it is so laid out that by making 55 a minimum of cuts and folds, an integral

protector results. This comprises the floor or base b, from which a lip b' is cut and bent at right angles to form the anchorage member. The rear wall c, and side wings c', are also initially bent at right angles, 60 while the retaining flanges c², are bent at right angles with the wings to bear upon the extended base b, when the wings are forwardly sprung or bent to extend at acute angles with the rear wall to afford free circulation about the inserted beam end, as indicated, in Figs. I and III. The extremities of the base b² are then bent up over the flanges c², and serve firmly to clamp or retain them in place, thus forming an integral 65 protector in the simplest and cheapest manner possible, from sheet metal of any suitable gage and in the size desired. The flanges, however, may be riveted in some of the heavier types, as shown at b³, Fig. III, 70 and dowel-pins b⁴, may be inserted in the floor or base of the protector, in lieu of the integral anchorage member provided in the construction above explained. Otherwise, the device of Fig. III conforms to that of 75 the preceding figures.

In Fig. IV, the integral construction is adhered to, except as to the provision of an angle iron b'', which riveted to the floor or base, serves to give some additional strength 85 thereto, and the flanges upon the side wings, moreover, are exteriorly riveted to the extended ends of the base. It will be understood, however, that the variable features embodying other types of anchorage member, or overlapped and self-retaining ends, either riveted or unriveted, are employed 90 interchangeably in practising my invention, which involves the use of an integral blank for forming all, or the major portion of the beam-end protector and anchor, substantially as I have herein described.

This device can be made with a minimum expenditure, both as to the cost of labor and metal employed, and by properly shaping 100 the beam-end, as shown in Fig. I, the self-releasing feature is readily obtained.

It will be appreciated that the gage of metal need be made only as heavy as is actually required for each particular size, or the special location of the protector, while the distribution of the load may be varied as well, merely by extending the base.

Having now explained the preferred embodiment of my invention, I claim as new, 110

and desire to secure by Letters Patent, the following:—

1. An integral beam-end protector, shaped from a sheet metal blank and comprising a base portion, and substantially vertical rear and side walls, forming therewith a receptacle opening from the top and front, bottom flanges provided upon the side walls, and overlapping ends upon the base portion, bent up to inclose and retain the flanges and side walls in position, substantially as set forth.

2. An integral beam-end protector shaped from a sheet metal blank and comprising a base portion, and substantially vertical rear and side walls, forming therewith a receptacle opening from the top and front, an anchorage member stamped up from the base portion within said receptacle, bottom flanges provided upon the side walls, and overlapping ends upon the base portion, bent up to inclose and retain the flanges and

side walls in position, substantially as set forth.

3. A beam-end protector and anchorage 25 shaped from an integral sheet metal blank, comprising a base portion, a rear wall bent vertically therefrom, and side wings forwardly extending at acute angles to inclose the beam-end; the terminals of the base portion being bent up and around the bottom portions of said side wings in order to retain the side wings in position, and an anchorage member integrally shaped from the base portion of the receptacle thus formed, 30 substantially as set forth.

Signed at Cleveland, Ohio, this 12th day of Feb'y 1909, in the presence of two subscribing witnesses.

JULIUS TUTEUR.
